PAGE 4

Fig 4

Fig. 5

FIG. 1 is a front elevation of a vertical milling machine showing my new design;

FIG. 2 is a right side elevation thereof;

FIG. 3 is a rear elevation thereof;

FIG. 4 is a left side elevation thereof; and

FIG. 5 is a top plan view thereof.

In the several views, principal moving parts are shown in their median ready positions.

I claim:

The ornamental design for a vertical milling machine, substantially as shown and described.
